GIRDLER CORPORATION, OF LOUISVILLE, KENTUCKY, A CORPORATION OF DELA-
WARE

METHOD OF AND DIE MANDEL FOR SHAPING CURVED TUBES

Application filed June 10, 1930. Serial No. 460,125.

This invention relates to the art of shaping tubes or the like, and more particularly to an improved die mandrel, for instance, of the type disclosed in United States Patent 5 No. 1,353,714 to R. H. Böhling, September 21, 1920.

In the shaping of straight tubes into bends, the wall forming the inner curved portion thereof is compressed or upset as the bend is 10 formed. This upsetting has a tendency to increase its thickness, but is offset through the agency of a mandrel of the type referred to in said patent, by expanding the diameter of the tube during shaping operations. In 15 this manner the surplus material is distributed circumferentially effecting thereby a tube bend having walls of equal thickness throughout. However, straight tubes as commercially manufactured are seldom perfectly 20 uniform in wall thickness so that they are subjected to differential strains which effect a torsional influence thereon as they are being forced over the die mandrel. Torsional tendencies might also be produced during the 25 shaping operation as a result of unequal heating of the tube or other irregular factor which will render one part of said tube more susceptible than another to stretching or compression under stresses. These varying 30 influences often have the effect of twisting said tube from the plane in which it is initially started in shaping relationship with the die. Thus the resultant tubes often have to 35 be subjected to a further operation to bring the axis into a single plane.

The present invention provides means for confining every element of the tube during 40 shaping operation so that regardless of any irregular influences on said tube, its resultant bent form will have its axis disposed in one plane.

The present invention also provides a method of shaping tubes over a die mandrel, which 45 includes the step of forcing said mandrel and said tubes into keyed relationship during shaping operations.

In a concrete exemplification of the present invention, the tube in being forced over a die mandrel is expanded and forced into a depression or groove provided in the tube-

expanding portion of the mandrel and extending lengthwise thereof. In this manner a corresponding projection in the inside of the tube is formed during the bending operation, this projection engaging said depression 55 and serving to key said tube against twisting movement. This projection may take the form of a rib or key extending inside along the inner curved portion of the tube and may be forged by a correspondingly shaped groove 60 or key-way in the inner curved portion of the die mandrel. If desired, and if the torsional stresses are excessive, the inside surface of the outer curved portion of the tube being bent may be similarly provided with a rib 65 formed by a correspondingly disposed key-way on the die mandrel. Either one or both of these ribs may be provided. However, the inner curved portion of the tube is the portion 70 which is subjected to greater metal displacing force, so that a deeper rib or projection is formed thereon than would be formed in the inside of the outer curved portion of the tube. Therefore if only one rib 75 is to be used, it is preferable to employ the one disposed in the inner or shorter radius portion of the tube.

The rib formed as a result of this improved bending may sometimes be objectionable. The present invention, therefore further provides means for removing this rib after it is 80 formed, and after it has served its function but before the shaping operation is completed. This can be effected by providing in the path of the tube rib a projecting edge 85 which serves to iron out or shear off said rib.

Although the novel features which are believed to be characteristic of this invention will be particularly pointed out in the appended claims, the invention itself, as to its objects and advantages, the mode of its operation, and the manner of its organization, may be better understood by referring to the following description taken in connection 90 with the accompanying drawings forming 95 a part thereof, in which,—

Figure 1 is a top plan view of the die mandrel,

Fig. 2 is a side elevation of the die mandrel,
Fig. 3 is a side elevation partly in section

of the tube after being forced along the die mandrel.

Fig. 4 is a bottom plan view of the tube after being forced along the die mandrel,

5 Fig. 5 is a top plan view of a modified form of die mandrel,

Fig. 6 is a top plan view of a form of die mandrel designed to remove the rib,

10 Fig. 7 is a section taken on the line 7—7 of Fig. 6.

Fig. 8 is a side elevation partly in section of a tube after being forced over the mandrel of Fig. 6 and

15 Fig. 9 is a bottom plan view of a tube shown in Fig. 8.

Like reference characters denote like parts in the several figures of the drawings.

20 In the following description and in the claims parts will be identified by specific names for convenience, but they are intended to be as generic in their application to similar parts as the art will permit.

25 In the specific form shown in Figs. 1 and 2 the die mandrel has a shank 10, one end of which may be frusto-conical to facilitate the entry of the tube into forcing relationship therewith. The other end of the shank 10 merges into the bend-forming portion 11 having an outside curvature 12 which corresponds

30 to the curvature of the resultant bent tube and which has a point A as a center of its curve. The axis 13 of the mandrel is constituted by a plurality of inter-connected curved elements, and includes a circular portion from B to C having A as a center, a circular portion from C to D having a point E as a center, and a circular portion D to F having a point G as a center, and the axis of the shank 10 as a tangent. The inside curvature

35 of the mandrel is constituted by a circular portion from J to K having A as a center, and a circular portion from L to M having H as a center, these two circular portions being joined by a tangential element K to M.

40 45 This relationship between the centers of the curved elements constituting the mandrel has not been shown as a limitation to the particular type of mandrel to which the present invention can be applied, but is merely indicated to give a general idea of the shape of one particular type of mandrel to which the invention may be applied. It is not intended to limit the adaptation of the present invention to any particular type of die mandrel

50 55 except to a mandrel over which the tube is forced endwise to curve it. The mandrel is of gradually increasing diameter if the tube is to be expanded and is curved laterally or given an eccentric projection if the tube is to be curved.

60 To provide a suitable resistance against torsional tendency of the character above referred to, the inside curvature of the mandrel is provided with a groove or key-way 14, which extends lengthwise and preferably

along the entire length of the curved part of said mandrel. As the tube is being forced along said mandrel it is expanded and the inside wall is subjected to stresses due to the eccentric projection of the die mandrel and these tend to distribute circumferentially the metal which would otherwise tend to produce increased thickness. The key-way 14 acts as a die for the upset portion of the tube and forms a rib or key 15 along the inside surface of said tube. This rib 15 is positioned in keyed relationship with the groove 14 thereby obviating the displacement of the elements of the tube from their plane of movement.

15 If desired, the outside curved portion of the mandrel may be provided with a key-way 16 which similarly forms a rib 17 on the outside curvature of the tube. It should be noted that the outside curved portion of the tube during forcing operations is under tension and subjected to less stresses than the inner portion. The result is that a much lesser deforming of the metal takes place on the outside radius of the tube than on the inside radius. This may result in deficient gripping relationship between said rib 17 and the engaging key-way 16. To compensate for this possible deficiency in gripping relationship, the key-way 16 may be made wider than the key-way 14 so that a wider rib is correspondingly formed, as shown in Fig. 5.

20 The ribs formed on the inside of the tubes as a result of forcing operations may in some cases be objectionable. To eliminate these ribs before the end of the shaping operation, a mandrel is provided of the type shown in Figs. 6 and 7. In this form the key-way 18 extends only partially along the inner or shorter wall of the mandrel so as to form a projecting edge 20 in the path of the rib. This projecting edge serves to iron out or shear off the rib. If a shearing action is desired the edge 20 may be sharpened and tempered accordingly. If an ironing action, however, is desired, it is preferred to slightly round off this edge or provide a gradual approach thereto by an extension merging with the base curvature of the key-way 18.

25 It should be noted that this projecting edge 20 dams the passage of the scale and any shavings which collect in the key-way 18 and may prevent them from passing to the end of the mandrel. Such scale and shavings may eventually clog up the key-way 18 and collect in sufficient amounts to affect the ultimate shape of the tube. To obviate this undesirable collection of scale and the like a conduit or hole 21 is provided between the projecting edge 20 and the end of the mandrel to permit the scale to pass out through the end of the mandrel.

30 A tube as made by the die mandrel shown in Figs. 6 and 7 is shown in Figs. 8 and 9.

35 It should be noted that the relative forcing of the tube and die mandrel can be effected

by drawing or forcing the mandrel through the tube or by forcing the tube over the die mandrel.

Of course, it is preferable to have the 5 groove in the mandrel to form a rib in the tube because such rib does not weaken the wall, but where such weakness is not important, the mandrel might have a rib to form a groove in the tube.

10 Having thus described our invention, what we claim as new and desire to secure by Letters Patent is:

1. A mandrel for expanding and curving tubes, said mandrel having an eccentric projection to expand and bend the tube, and a key-way extending along the inner curvature thereof, and adapted to forge a corresponding rib in the inside of the tube being forced over the mandrel, whereby all of the elements of said tube are confined to plane movement during shaping operation.

2. A tube-expanding and curving mandrel having a body portion of gradually increasing diameter and laterally curved, a key-way thereon adapted to forge a corresponding rib inside the tube being forced over the mandrel, whereby the elements of said tube are confined to plane movement during shaping operations, and means for substantially eliminating said rib before said tube is advanced outside of engaging relationship with said mandrel.

3. A tube-bending mandrel having a laterally curved body portion with a key-way thereon adapted to forge a corresponding rib on the inner surface of the tube being forced over the mandrel, and a projecting edge on said mandrel in the path of said rib adapted to eliminate said rib before said tube is advanced away from engaging relationship with said mandrel.

4. A tube-shaping mandrel having a key-way thereon adapted to forge a corresponding projection on the inside of the tube being forced over the mandrel, a cutting edge on said mandrel for shearing off said rib before said tube is advanced away from forcing relationship with said mandrel, said mandrel having a conduit leading from the field of action of said cutting edge to the end of the mandrel for obviating the clogging of the key-way with metal shavings or scales.

5. A tube-shaping mandrel having a key-way thereon adapted to forge a corresponding rib on the inner surface of the tube being forced over the mandrel, and a projecting edge on said mandrel in the path of said rib, said edge being adapted to eliminate said rib before said tube is advanced away from forcing relationship with said mandrel, said mandrel having a conduit leading from the field of action of said projecting edge to the end of the mandrel for obviating the clogging of the key-way with scales.

6. A tube-shaping mandrel having a key-

way thereon adapted to forge a corresponding rib on the inside of the tube being forced over the mandrel, and a projecting edge on said mandrel in the path of said rib, said edge being adapted to eliminate said rib before said tube is advanced away from forcing relationship with said mandrel.

7. The method of forming curved tubes, which includes forcing a straight tube over a die mandrel having a key-way on the inner 75 curved surface, and thereby forging the excess material of said tubes into the key-way during shaping operations, and substantially eliminating the rib formed thereby before said tube is advanced outside of engaging 80 relationship with said mandrel.

8. A mandrel for expanding and curving tubes, said mandrel having a body portion of gradually increasing diameter and laterally curved, and a key-way extending lengthwise 85 thereof and adapted to forge a corresponding rib in the plane of the center of curvature of the mandrel, and along the inner surface of the wall of the tube being forced over said mandrel, the interengagement of said rib and said key-way serving to confine the movement of the tube to said plane during the shaping operation.

9. The method of forming curved tubes, which includes forcing a straight tube over a curved mandrel of larger diameter than the internal diameter of the tube to thereby expand the tube, reduce the wall thickness and curve the tube, and forging a portion of the metal of the wall of the tube into an inwardly 100 extending rib in the plane of curvature of the tube during the expanding and curving operation to thereby maintain the tube in a predetermined plane.

Signed at Louisville in the county of Jefferson and State of Kentucky this 29th day of May, 1930.
